UNITED STATES PATENT OFFICE.

CHARLES F. BROWN, OF READING, MASSACHUSETTS, ADMINISTRATOR OF
JAMES ALFRED LAMPLUGH, DECEASED.

BICYCLE-SADDLE.

SPECIFICATION forming part of Letters Patent No. 595,599, dated December 14, 1897.

Application filed October 8, 1897. Serial No. 654,517. (No model.) Patented in England March 8, 1892, No. 4,588.

To all whom it may concern:

Be it known that JAMES ALFRED LAMPLUGH, deceased, late of Birmingham, in the county of Warwick, England, did invent 5 certain new and useful Improvements in Bicycle-Saddles, (for which Letters Patent of Great Britain were granted to him March 8, 1892, No. 4,588,) of which the following is a specification.

10 This invention relates to a bicycle-saddle which is of comparatively stiff material, such as sole-leather, and suitable metallic supporting-fixtures therefor, and has a widened rear portion constituting the seat proper and 15 a narrower portion projecting forward from the seat portion and constituting a horn or pommel.

The invention has for its object to provide certain improvements in the construction of 20 a saddle of this class, whereby the forward portion, while affording the usual lateral support for the rider's legs, will present a yielding top surface adapted to prevent injurious pressure on the perineum, thus overcoming 25 a well-known objection to ordinary saddles of this type in which the portion of the saddle on which the perineum bears is practically rigid, as in the ordinary sole-leather saddle.

30 The invention consists in a bicycle-saddle constructed substantially as hereinafter described and claimed.

Of the accompanying drawings, forming a part of this specification, Figure 1 shows a 35 side elevation of the saddle. Fig. 2 shows a bottom plan view. Fig. 3 shows a longitudinal section. Fig. 4 shows a longitudinal section of a modified construction.

In the drawings, *a* represents the seat portion, and *a'* the horn portion or pommel. These parts may be of the usual general form and construction and are preferably made of a single piece of sole-leather suitably molded and attached to the usual or any suitable metallic supporting-pieces.

In carrying out the invention an elastic cushion is provided extending lengthwise of the saddle throughout the greater part of the length of the horn, said cushion being located 50 between and projecting above the side portions of the horn and arranged to support the

perineum of the rider and prevent injurious pressure thereon. Said cushion is preferably constructed and applied as follows: In the comparatively stiff body of the saddle a longitudinal opening *a'* is cut, extending from the forward part of the seat portion lengthwise of the pommel and nearly to the forward end of the latter, the opening terminating just behind the metallic fixture, which holds the forward end of the horn in place. A flexible pocket *k* is secured to the edges of this opening and fills the same, and said pocket is designed to be inflated by air under pressure, and preferably by being supplied with a thin rubber bag having a valve for inflating purposes and arranged to be admitted into the pocket through a suitably-laced slit therein. However, the pocket might be inflated without the inner bag, or it might simply contain air at atmospheric pressure.

It has been found by practical experience that this improved saddle relieves the rider of the discomfort due to the pressure of the perineum on a comparatively hard surface 75 and is at the same time sufficiently stable to enable the rider to exert his muscular force to good advantage, it being in this respect more desirable than so-called "pneumatic" saddles, in which the entire supporting-surface is air-cushioned and therefore unstable.

In the arrangement shown in Fig. 4 the saddle-top is made in two pieces—a strong under piece *f* and a thin covering-piece *g*—and between these pieces is inserted an air-cushion *i*, extending along the pommel. An air-cushion *h* is also introduced between the two layers of leather at the cantle of the saddle.

In order to further the yielding property of the pommel portion of the saddle, the usual casting fitting under the forward end of the pommel and unyieldingly supporting the same is dispensed with, and instead the arch of leather is left without a rigid support, the sides being connected by a shouldered cross-pin *d*, whose reduced ends pass through the leather and are headed on the outer sides of the same, the pin being free to turn. A screw-threaded adjusting-rod is entered through a hole in the said cross-pin and has a hooked end to engage the usual spring foundation *e*.

The invention is not limited to the described

details of construction, and the same may be variously modified without affecting the essential features of the invention.

The saddle may have a row of orifices *o o* 5 for purposes of ventilation.

What is claimed is—

1. A bicycle-saddle comprising a seat portion, a horn or pommel projecting forward therefrom and having an elastic cushion at 10 the central portion thereof, the portion of the saddle at the rear of said cushion being of comparatively unyielding construction, relatively to said cushion.

2. A bicycle-saddle comprising a seat portion, a horn or pommel having a flexible casing or pouch extending lengthwise of the pommel, and an elastic cushion in said casing; the portion at the rear of said cushion being of a comparatively unyielding construction, 20 relatively to said cushion.

3. A bicycle-saddle having a top composed of two layers of material, a strong and stiff under layer, and a thinner and more flexible

upper layer, and one or more air-cushions between the layers; the portion of the saddle 25 not occupied by a cushion being of a comparatively unyielding construction, relatively to said cushion.

4. A bicycle-saddle comprising a seat portion, a horn or pommel with an opening extending longitudinally of the horn for the greater portion of its length, and an elastic cushion arranged in said opening; the portion at the rear of said cushion being of a comparatively unyielding construction, relatively 30 to said cushion.

In testimony whereof I have signed my name to this specification, in the presence of two subscribing witnesses, this 5th day of October, A. D. 1897.

CHARLES F. BROWN,
Administrator of the estate of James Alfred Lamplugh.
